UNITED STATES PATENT OFFICE.

JOHN L. THOMPSON, OF MINNEAPOLIS, MINNESOTA, ASSIGNOR OF FIVE-EIGHTHS TO WALTER A. BENNET, OF ST. LOUIS, MISSOURI, AND EDWARD McNAMEE, OF ST. PAUL, MINNESOTA.

HUB-ATTACHING DEVICE.

SPECIFICATION forming part of Letters Patent No. 372,392, dated November 1, 1887.

Application filed June 28, 1887. Serial No. 242,734. (No model.)

To all whom it may concern:

Be it known that I, JOHN L. THOMPSON, a citizen of the United States, residing at Minneapolis, in the county of Hennepin and State 5 of Minnesota, have invented certain new and useful Improvements in Hub-Attaching Devices, of which the following is a specification.

My invention relates to means for connecting hubs to the spindles of vehicle-axles; and 10 the improvements, generally stated, consist of an axle-box having its outer end closed, a thimble-skein attached to the spindle, and a butting-disk attached to the inner end of the hub and abutting against the end of the thimble-skein.

The improvements are illustrated in the accompanying drawings, in which—

Figure 1 is a longitudinal sectional view of the hub and spindle provided with my improvements. Fig. 2 is a detached view of the thimble skein, butting-disk, and spindle. Fig. 3 is a transverse sectional view on the line *x* of Fig. 1. Fig. 4 is a view of the side of the disk which abuts the skein, showing a washer 25 attached to the disk. Fig. 5 is a sectional view of the disk on the line *y* of Fig. 4. Fig. 6 is a view of the outer end of the hub. Figs. 7, 8, and 9 are details of a modified construction of the butting-disk, and Fig. 10 is a sectional view of the same connected with a thimble-skein which has a flange on its inner end.

A in the drawings represents the usual spindle of an axle, *A'*.

B is an ordinary wagon-hub, in which is secured a tapering axle-box, *C*, of suitable metal. The outer end, *c*, of the box *C* is closed, and may have any desired outward shape—as, for example, that of a nut, as shown in the drawings. The interior of the box end is preferably concave, and in it is inserted a wooden or other suitable plug, *D*, against which the end of the spindle abuts to limit the inward movement of the hub.

E is the thimble-skein on the spindle *A*, 45 with its outer end flush with the end *A* of the spindle, and fastened to the spindle by a pin, *p*, extending through the skein and spindle. The inner end of the thimble-skein should be chilled to insure durability.

At the inner end of the hub is a butting-disk, 50 *F*, attached to the hub by bolts *d*, fast in the end of the hub, and nuts *e*, that screw down onto the disk. The inner end of the thimble-skein abuts against the disk, and the outer movement of the hub is thereby limited. The 55 bolt-holes in the disk are elongated slots *f*, having one end, *f'*, enlarged for the nuts to pass through as the hub is being put on or taken off. When the hub is in place, the disk is rotated sufficiently to bring the narrower 60 portions of the slots *f* under the nuts, and the nuts are then screwed down to hold the disk securely against the end of the hub. These narrow portions of the slots have suitable countersinks, *f''*, to receive the nuts when 65 screwed in, to prevent the slipping of the disk on the hub when in place. The collar or hub *f'''* of the disk may be made angular, so that it can be grasped by a wrench to turn it; or, if made round, it may have a lug, *f''*, with a hole, 70 into which a pin can be inserted to rotate the disk. When in place, the collar *f'''* is free from contact with the shoulders *a* of the axle, and the bearing-surfaces to limit the longitudinal 75 movement of the hub are the skein against the butting-disk at the inner end and the spindle and skein against the plug *D* at the outer end.

The disk *F* may be of cast metal having a steel washer, *w*, let into an annular recess around the central opening to abut against the 80 end of the skein, and the washer may be secured by screws *w'*, so that it can be readily removed. When the frictional surfaces become worn and it is desirable to tighten them, a thicker washer may be substituted for the 85 washer *w*; or a loose washer may be interposed between the end of the skein and the butting-disk after removal of the skein by the withdrawal of the pin *p*; or the skein may be replaced by another of the proper length. 90

In the modified construction the butting-disk is shown in Figs. 6 to 10, which is more particularly adapted for light vehicles, two plates being used, the one, *G*, being permanently attached to the hub by screws through the 95 screw-holes *g*, and the other, *H*, made adjustable on the surface of the former. A bolt, *d*, and a nut, *e*, are used to tighten the outer or

butting plate in the manner heretofore described. The sides of the plate H are guided and held in place by overhanging lugs g' on the plate G, and the plate H has slots h, which coincide with the lugs g' when the bolt and nut are in the enlargement f' of the slot f, as shown in Fig. 7, so that the plates can be separated. The plate G may be dispensed with by having the lugs g' cast on the margin of the hub-band b. The collar of the plate H is shown of angular form, to be more easily grasped by a wrench to turn the plates.

The plates G and H are shown in vertical transverse section in Fig. 10, with a thimble-skein in place having a flange, e, fitting within the central opening of the plate G and abutting against the plate H, thus affording a wider wearing-surface for the end of the skein than in the form of skein first described.

In the lighter kinds of vehicles the plug D in the end of the box may be dispensed with by having the spindle and box constructed to form a suitable end bearing, and an oil-hole for injecting oil may be made in the end of the box and provided with a screw-plug for closing it.

Having described my invention, what I claim, and desire to secure by Letters Patent, is—

1. In combination with a hub and spindle, 30 an axle-box closed at its outer end and secured in the hub, a thimble-skein fastened on the spindle with its outer end flush with the end of the spindle and its inner end flush with the end of the axle-box, a suitable bearing plug 35 between the spindle end and box end to prevent inward movement of the hub, and a butting-plate secured to the end of the hub and abutting the end of the thimble-skein to prevent outward movement of the hub, substantially as set forth.

2. In combination with an axle, its hub and spindle, an axle-box closed at its outer end and providing a bearing for the spindle end, a thimble-skein with its outer end flush with the 45 spindle end and its inner end flush with the end of the axle-box, a pin securing the skein to the spindle, a butting-plate furnishing a bearing for the inner end of the skein, and means, as described, for attaching the plate to the hub 50 end, substantially as and for the purpose set forth.

JOHN L. THOMPSON.
